UNITED STATES PATENT OFFICE.

ALBERT L. BOWEN, OF WORCESTER, MASSACHUSETTS, ASSIGNEE TO CHARLES K. PEVEY, OF WORCESTER, MASSACHUSETTS.

EXTENSION TOP OR CANOPY FOR VEHICLES.

No. 876,768.

Specification of Letters Patent.

Patented Jan. 14, 1908.

Application filed June 20, 1907. Serial No. 379,962.

To all whom it may concern:

Be it known that I, ALBERT L. BOWEN, a citizen of the United States, residing at Worcester, in the county of Worcester and State of Massachusetts, have invented certain new and useful Improvements in Extension Tops or Canopies for Vehicles; and I do hereby declare the following to be a full, clear and exact description of the invention, such as will enable others skilled in the art to which it appertains to make and use the same.

My invention relates to extension tops or canopies for vehicles.

It has for its main object to provide a canopy which can be extended or folded by one man while in the vehicle.

Another object is to provide means for securing the canopy bows when folded so that they will not rattle.

The invention consists in the features of construction and combinations of parts hereinafter described and specified in the claims.

In the accompanying drawing, illustrating the preferred embodiment of my invention: Figure 1 is a perspective view of the body of an automobile with the framework of the canopy extended and the cover of said framework removed. Fig. 2 is a broken side elevation of said automobile body showing the framework of the canopy folded and secured. Fig. 3 is an enlarged broken detailed view showing the construction of pivot-clamps, and Fig. 4 is an enlarged sectional view on the line x-x of Fig. 2.

Referring more particularly to the drawing, 1 designates the body of an automobile, 2 the rear seat and 3 the front seat thereof. A pivot-pin 4 is secured to each side of the rear seat and on said pins is mounted the main or upright bow 5 of the rear section of the canopy frame. A second or auxiliary bow 6 is pivoted to said bow 5 at 7 and extends rearward therefrom. The main or upright bow 8 of the front or extensible section of the canopy frame is pivotally mounted, when folded, upon pins 9 of the bow 5. A second or auxiliary bow 10 is pivoted to the bow 8 and extends forward therefrom. When the front section of the frame comprising the bows 8 and 10 is extended, it is mounted on pins 11 secured to the sides of the front seat.

Between the main bows 5 and 8 respec-

tively of the rear and front sections of the frame are arranged two short bows 12 and 13 having their upper horizontal portions hinged together at 14. The ends of the rear short bow 12 are pivotally connected to the bow 5 by means of pivot-clamps 15. The ends of the front short bow 13 are similarly mounted on pivot-clamps 15 fastened to the bow 8. Flexible straps or bands 17 of any suitable material connect the hinged upper portions of said short bows and the horizontal portion 18 of the bow 5. Said straps or flexible connections are of such length as to limit the movement of the short bow 12 to a position where its vertical portions are oblique to the bow 5 and its horizontal portion is in substantially the same horizontal plane as the horizontal portions of the main bows 5 and 8 when the frame is extended. Other flexible connections or straps 19 are preferably fastened across the top of the frame, being secured to the bow 6, then to the bow 5, then to the bow 8 and then to the bow 10. Front and rear guy straps 20 and 21 respectively are adapted to secure the bow 10 to the front of the body and the bow 6 to the rear thereof when the frame is extended. If heavy or strong material is used for covering the frame of the canopy, the straps or flexible connections 17 and 19 and the guys 21 may be dispensed with but it is preferable to use them to prevent wear and strain on the covering.

Each of the pivot-clamps 15 and 16 has two flexible gripping members 22 which may be bent to conform to different sizes of bows. Said clamps are prevented from slipping by bolts 23 passed through the bows and carrying nuts 24. Each clamp has two inwardly projecting lugs, a short one 25 above the pivot and a longer one 26 below it. The upper lugs have their ends grooved at 27 to fit the short bows when the frame is folded. The lower lug on the clamp 15 has its end grooved as at 28 to receive the beveled end or tongue 29 of the lower lug on the opposite clamp 16. By means of this construction of clamps the bows when secured by the straps 30 will be prevented from rattling when they are folded.

It will be observed that the short bows and connections 17 will brace or support the weight of the extensible section of the frame as it is being moved into its extended position and adjusted on the pins 11 mounted on

the sides of the front seat. Because the weight of said front section is thus upheld, one man is able to extend or fold the canopy alone while in the vehicle, whereas it requires one man on each side of the car to carry the extensible section of a canopy of ordinary construction forward and mount it on the front pins. In adjusting the old form of canopy the front bows are liable to sag or slip and scratch the body of the vehicle whereas when my invention is used this is impossible. The pivot clamps I employ are neat in appearance and will not disfigure a nice top.

15 1. I claim:

1. A canopy frame for vehicles comprising a rear section and a front extensible section, each having an upright bow, a pair of short bows pivotally mounted on said upright bows and having their upper horizontal portions hinged together, and flexible connections between the short bow pivoted to the rear upright bow and said rear upright bow for the purpose specified.

25 2. A canopy frame for vehicles comprising a rear section and a front extensible section, each having a main or upright bow, a pair of short bows pivotally mounted on said upright bows and having their upper horizontal portions hinged together, and flexible connections between said hinged portions of said short bows and the upper horizontal portion of the upright bow of the rear section for the purpose specified.

35 3. In a canopy frame for vehicles, the combination, with a plurality of long bows and short bows, of pivot-clamps mounted on said long bows and having means to pivot said short bows, said clamps having project-

40 ing lugs provided with tongue and grooved ends respectively adapted to engage each

other when said bows are folded, and means to secure said bows in their folded position.

4. In a canopy frame for vehicles, the combination, with a plurality of long bows and short bows arranged between them, of pivot clamps mounted on said long bows and having means to pivot said short bows, said clamps having two sets of projecting lugs, one set being arranged above the pivots and 50 having their ends grooved to fit the vertical portions of said short bows, the other set of lugs being longer and arranged below said pivots with their ends tongue and grooved respectively and adapted to engage each 55 other when said bows are folded, and means to secure said bows in their folded positions.

5. In a canopy frame for vehicles, the combination, with a plurality of long bows and short bows arranged between them, of 60 pivot clamps mounted on said long bows and having means to pivot said short bows, said clamps having flexible portions to engage the opposite sides of said long bows and adapted to be bent to conform to different 65 sizes of bows, said clamps also provided with two sets of projecting lugs, one set being arranged above the pivots and having their ends grooved to fit the vertical portions of said short bows, the other set of lugs being 70 longer and arranged below said pivots with their ends tongue and grooved and adapted to engage each other when said bows are folded, and means to secure said bows in their folded positions. 75

In testimony whereof, I affix my signature, in presence of two witnesses.

ALBERT L. BOWEN.
